(57) **CLAIM**

The ornamental design for a buckle strap as shown and described.

DESCRIPTION

FIG. 1 is a perspective view of a buckle strap showing my new design;

FIG. 2 is another perspective view thereof;

FIG. 3 is a third perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of the buckle strap where the buckle strap is in a folded state;

FIG. 11 is an enlarged view of portion 11 shown in FIG. 1;

FIG. 12 is an enlarged view of portion 12 shown in FIG. 3; and,

FIG. 13 is an enlarged view of portion 13 shown in FIG. 6. The dash-dash broken lines in the drawings depict portions of the buckle strap that form no part of the claimed design. The dot-dash broken lines represent the boundary of the enlarged portions and form no part of the claimed design.

1 Claim, 13 Drawing Sheets
